DESIGN FOR A TEXTILE FABRIC OR SIMILAR ARTICLE

Roger Weiss, Brooklyn, N. Y., assignor to Primrose Tapestry Co. Inc., Rome, Ga., a corporation of Georgia

Application October 11, 1939, Serial No. 87,623

Term of patent 7 years

To all whom it may concern:

Be it known that I, Roger Weiss, a citizen of the United States, residing at 143 Lenox Road, Brooklyn, in the county of Kings and State of New York, have invented a new, original, and ornamental Design for a Textile Fabric or Similar Article, of which the following is a specification, reference being had to the accompanying drawing, forming a part thereof.

The figure is a plan view of a textile fabric showing my new design.

I claim:

The ornamental design for a textile fabric or similar article, substantially as shown.

ROGER WEISS.
